Primary Examiner — Leanne Was-Englehart

(57) **CLAIM**

The ornamental design for a sample box, as shown and described.

DESCRIPTION

FIG. 1 is a front perspective view of a sample box in a closed configuration in accordance with my new design;
FIG. 2 is a front elevation view thereof;
FIG. 3 is a rear elevation view thereof;
FIG. 4 is a top plan view thereof;
FIG. 5 is a bottom plan view thereof;
FIG. 6 is a right side view thereof, the left side view being a mirror image thereof;
FIG. 7 is a rear perspective view thereof;
FIG. 8 is a front perspective view thereof, in an open position of use, showing an exemplary article inserted into the sample box;
FIG. 9 is a front perspective view thereof, without an article inserted into the sample box;
FIG. 10 is a front elevation view thereof;
FIG. 11 is a rear elevation view thereof;
FIG. 12 is a top plan view thereof;
FIG. 13 is a bottom plan view thereof;
FIG. 14 is a right side view thereof, the left side view being a mirror image thereof;
FIG. 15 is a rear perspective view thereof;
FIG. 16 is a front perspective view thereof, in another open position of use, showing an exemplary article inserted into the sample box;
FIG. 17 is a front perspective view thereof, without an article inserted into the sample box;
FIG. 18 is a front elevation view thereof;
FIG. 19 is a rear elevation view thereof;
FIG. 20 is a top plan view thereof;

(Continued)

FIG. 21 is a bottom plan view thereof;
 FIG. 22 is a right side view thereof, the left side view being a mirror image thereof; and,
 FIG. 23 is a rear perspective view thereof.
 The broken lines illustrate environmental subject matter or parts of the article. None of the broken lines form part of the claim design.

1 Claim, 23 Drawing Sheets
